FURNACE FOR THE COMBUSTION OF LIGNITE AND SEMIBITUMINOUS COAL

Oliver S. Bowman, Colorado Springs, Colo.

Application August 29, 1938, Serial No. 227,325

4 Claims. (Cl. 110—30)

This invention relates to improvements in furnaces and has reference more particularly to furnaces for the combustion of lignite and semi-bituminous coal.

It has been estimated that over fifty per cent of the coal in the United States is comprised of two different grades of lignite. This type of coal differs greatly from anthracite and bituminous coal and requires different types of furnaces for their most efficient combustion. Lignite coal slacks very easily and crumbles quite readily when subjected to heat and therefore offers great resistance to the passage of air, thereby making it difficult to procure efficient combustion. Experience has shown that lignite coal can be burned with the greatest efficiency in layers from two to four inches thick and that if the coal is positioned between spaced vertical grates so as to form a thin vertical wall that is ignited at the bottom and the air necessary for combustion is passed through this wall of coal, a highly efficient combustion is obtained. Since the combustion takes place at the lower end of the wall the ashes will drop down and will not clog the passageway for the air and gaseous products of combustion. Since it is rather impractical to employ a straight vertical wall of coal, it is made cylindrical by employing spaced concentric cylindrical grates in the manner to be herein described.

It is the object of this invention to produce a furnace having concentric cylindrical grates spaced apart so as to provide an annular cylindrical space for the reception of the solid fuel and to so arrange the air supply and the draft that the air will flow transversely through the layer of coal.

Another object is to provide a grate construction which will keep the openings in the grates from clogging and which will permit the ash to be readily removed and the consumed fuel replaced.

A further object is to produce a furnace in which heated air is mixed with the gaseous products of combustion so as to oxidize any carbonaceous material present in the gases and thus prevent smoke, and in addition obtain the heat resulting from the oxidation.

The above and other objects that may become apparent as this description proceeds are obtained by means of a construction and an arrangement of parts that will now be described in detail and for this purpose reference will be had to the accompanying drawing in which the invention has been illustrated and in which

Figure 1 is a vertical diametrical cross section through a furnace embodying the invention;

Figure 2 is a transverse section taken on line 2—2, Fig. 1;

Figure 3 is a fragmentary view, similar to the one shown in Fig. 1, and shows a different feed device;

Figure 4 is a fragmentary view, similar to the one shown in Fig. 1, and shows how a forced draft can be applied;

Figure 5 is an inside elevation of one section of the inner grate;

Figure 6 is a transverse section taken on line 6—6, Fig. 5;

Figure 7 is a vertical section taken on line 7—7, Fig. 5;

Figure 8 is an elevation showing the outside of a section of the outer grate.

Figure 9 is a cross section taken on line 9—9, Fig. 8, and

Figure 10 is a section taken on line 10—10, Fig. 8.

In the drawing the invention has been shown as embodied in a furnace having a circular combustion chamber formed by a wall 11 of fire brick. A grate support ring 12 is built into the inner surface of the wall and has an inwardly projecting flange 13 on which an annular grate 14 is supported. The central opening in the grate is closed by a circular dump grate 15. A pinion 16, secured to the inner end of shaft 17 engages with teeth on the under surface of the grate and when shaft 17 is oscillated the grate will also be oscillated. The furnace wall has been shown as provided with an ash compartment door 18 and cleanout openings provided with suitable closures 19. In the embodiment shown in Fig. 1 the gaseous products of combustion have been shown as escaping through flue 20 but the drawing is illustrative only and the heated gases may pass through an opening 21 and thence through the flues of a boiler or other heat interchange apparatus.

A cylindrical grate, constructed from a plurality of sections 22 like those shown in Figs. 8, 9 and 10, is supported from ring 12, each grate section has two outwardly projecting lugs 23 at its lower end, which extend over the grate ring in the manner shown in Fig. 1. The vertical edges of the grate section 23 are provided with grooves and tongues 24 and 25 respectively, and when the grate is assembled the tongue on one section engages the groove in the next section so as to form a cylindrical grate. Each grate section is also provided with an outwardly ex-

tending flange 23a along each vertical edge which engages the inner surface of the brick wall and these flanges serve to space the outer surface of the grate a predetermined distance from the inner surface of the brick wall to form passageways or channels 26 for the escape of the gases of combustion. It will be observed that each grate section is provided with a row of elongated openings 27 that are vertically spaced and extend transversely of the grate. From Fig. 10 it will be seen that the slots 27 are upwardly and outwardly inclined and that there are downwardly inclined overhanging lips 28 above each slot.

The inner grate is formed from a plurality of grate sections 29, similar in many respects to sections 22 but having a greater curvature. Each section is provided with inwardly extending radial lugs 30, which are perforated for the reception of stove bolts whereby the several sections necessary to form a complete cylinder can be held in assembled relation; four, six or any other number of sections can be used. In the embodiment illustrated four sections have been shown. Sections 29 are also provided with transverse slots 27 that are upwardly and inwardly inclined and have overhanging lips 28. Each section 29 is provided at its upper end with two upwardly and inwardly inclined, perforated lugs 31 by means of which they are attached to the conical top 32. Cap 32 has a plurality of radial openings for the reception of pipes 33 whose outer ends open into the channels 26 and supply heated air to the gaseous products of combustion for the purpose of consuming any unoxidized carbon particles contained therein. Pipes 33 also serve to support the inner grate which is suspended from the top of the outer grate by the pipes.

In the embodiment illustrated in Fig. 1 a gravity feed is employed and a container 34 is provided and this communicates with a pipe 35 of refractory material whose lower end terminates directly above the vertex of the conical cover, a slide 36 serves to cut off the flow of coal when necessary. When the fire is started the kindling is placed at the bottom of the annular space between the two concentric grates and this space is then filled with coal. Since the fire begins to burn at the lower edge of the coal and progresses upwardly, the coal will move downwardly by the actions of gravity so as to automatically replace the fuel as it is consumed, and final stage of the combustion takes place on the grate and the ash and the clinkers, if any, either rest on or pass downwardly through grate 14.

Since the air for combustion is supplied from the inside of the inner grate it will pass transversely through the layer of coal and the gaseous products of combustion will flow upwardly through channels 26. If any combustible gases are present among those flowing upwardly through channel 26 they will be consumed when they come in contact with the air which assures high efficiency and smokeless operation.

With this combustion chamber the coal can be burned in layers of any thickness and it is therefore possible to burn lignite slack or other slack because air for combustion can always pass through the thin layer.

The inner grate projects into such close proximity to the upper surface of grate 14 that a throat is formed that prevents any great amount of coal from flowing downwardly along the upper surface of grate 14 when the latter is stationary. Some live coals do cover the upper surface of

grate 14 on which the final stages of the combustion take place.

The dump grate is preferably provided with a tube 37 that provides a free air passage even if the surrounding grate surface becomes clogged. 5

If it is found desirable to employ forced draft, the lower end of the inner grate is closed by means of a plate 38 and an air duct 39 provided which connects the interior of the inner grate with a fan which has been indicated by 10 dotted lines at 40.

If a gravity feed like that shown in Fig. 1 is found to be undesirable, a mechanical trickle feed like that shown in Fig. 3 can be used. In this type of feed the coal is conveyed from a suitable hopper by a screw 41 which is preferably operated by a thermostatically controlled motor which has not been shown. The coal flows downwardly in tube 42 and is distributed by the cone cover 32. 15

It will be observed that the air slots 27 cannot choke and become ineffective because they incline downwardly towards the coal and are furthermore protected by the overhanging lips 28.

The specific construction of the grates is not 25 material as the same results may be obtained by specifically different structures. A cylindrical combustion space is believed to be preferable to a polygonal one but it is evident that the method here explained can be practised with specifically 30 different shapes of combustion spaces so long as means is provided for holding the coal in the shape of a thin wall so positioned that combustion takes place from the bottom and air is forced transversely through the wall of coal. 35

The inclination of slots 27 and the overhanging lips 28 are structural features of importance as they assure that the air will have free passage at all times.

The grates are preferably made from cast iron 40 but may be made from fire clay or any other suitable material.

It is, of course, to be understood that the combustion may take place all along the layer of coal from the bottom to the top. Since the 45 coal is ignited at the bottom it is evident that the combustion is completed at the bottom first and progresses upwardly. The gases are driven off near the top of the grates and pass into the channel or channels 26 where they come into 50 contact with heated air supplied through pipes 33 and are consumed.

Grate 14 can be oscillated by the means shown and described and clinkers can be dumped by 55 tilting grate 15.

Although space 26 is divided into a plurality of channels it is possible to have one annular channel or space 26.

In the drawing an embodiment has been shown in which the air is fed to the inside of the inner 60 grate and passes outwardly through the fuel. A reversal of this can readily be made in which the air is admitted to channel 26 and the gaseous products of combustion are renewed from the interior of the inner grate. Such reversal may 65 be desirable in some cases and applicant considers that this is included in the scope of his invention.

Having described the invention what is claimed 70 as new is:

1. A combustion chamber for the burning of solid carbonaceous fuel, comprising in combination two concentric vertically positioned perforated grates, spaced apart to form an annular cylindrical fuel space, a cover attached to the 75

5 top of the inner grate, and tubular air ducts attached at their inner ends to the cover and having their outer ends resting on and extending across the outer grate for supporting the inner grate and into the space outside of the outer grate for the purpose of conveying heated air to the outside surface of the outer grate.

10 2. A combustion chamber for the burning of solid carbonaceous fuel, comprising in combination, two concentric, vertically positioned cylindrical grates, spaced apart to form an annular cylindrical fuel space, a wall surrounding the outer grate and spaced therefrom to form a passage for the gaseous products of combustion, a cover attached to the upper end of the inner grate, the grates having slots extending circumferentially, means comprising tubes for supporting the inner grate from the outer grate and for conducting heated air from the top of the inner grate to the gas passages outside of the outer grate to complete the combustion of the gases.

15 3. A furnace for the combustion of carbonaceous fuel comprising, in combination, a cylindrical enclosing wall of refractory material, a grate ring positioned in the inner surface of the wall, a cylindrical grate supported on the grate ring with its outer surface spaced from the inner surface of the wall to form a channel for the escape of gaseous products of combustion, an inner cylindrical grate positioned within the first grate and spaced therefrom to provide an annular fuel space, a cover attached to the top of the inner

grate, and a plurality of tubular members radiating from the cover, said tubular members communicating with the interior of the inner grate at one end and with the channel surrounding the outer grate at the other end, the tubular members resting on the outer grate and serving to support the inner grate.

20 4. A furnace for the combustion of carbonaceous fuel, comprising in combination, a cylindrical enclosing wall of refractory material, a 10 grate ring positioned in the inner surface of the wall, a cylindrical grate supported on the grate ring with its outer surface spaced from the inner surface of the wall to form a channel for the escape of gaseous products of combustion, an 15 inner cylindrical grate positioned within the first grate and spaced therefrom to provide an annular fuel space, a cover attached to the inner grate, means for feeding fuel to the fuel space, means for introducing air into the inner grate; 20 the air passing from the interior of the inner grate through the fuel, products of combustion passing through the outer grate and into the space between the outer surface of the outer grate and the inner surface of the wall, and conduits connecting the interior of the inner grate with the top of the channel, whereby air is provided to complete the combustion of any combustible material in the gaseous products of combustion, said conduits serving also to support 25 the inner grate from the top of the outer grate.
